UNITED STATES PATENT OFFICE.

CORNELIUS HOOD, OF HARTFORD, CONNECTICUT.

IMPROVEMENT IN COMBINED BENCHES AND STEP-LADDERS.

Specification forming part of Letters Patent No. 147,003, dated February 3, 1874; application filed October 21, 1873.

To all whom it may concern:

Be it known that I, CORNELIUS HOOD, of Hartford, Hartford county, Connecticut, have invented a new and useful Combined Bench and Step-Ladder, of which the following is a specification, reference being had to the accompanying drawings, where—

Figure 1 is a view of the rear side of the implement folded up. Fig. 2 is an edge or side view of the same. Fig. 3 is a side view of the implement expanded into a bench or wash-form. Fig. 4 is a view of the implement expanded into a step-ladder. Fig. 5 is a view similar to Fig. 4, except that a shelf attached to the implement is adjusted for use.

The implement consists of a device which folds up very compactly, but can be adjusted into a wash-form, into a step-ladder without shelf, and into a step-ladder with shelf. The invention consists in the combinations of parts set forth in the claim at the end of this specification.

The letters $a a^1 a^2$ indicate a wooden frame, in which are rounds a^3 , serving as steps where the device is adjusted as a step-ladder. To this is hinged the frame $b b^1 b^2 b^3$, serving as a back support to the frame $a a^1 a^2$, when adjusted as a step-ladder. To the frame-sides $b b^2$ are pivoted two swinging frames, one composed of the two legs $c c^1$ and the cross-piece c^2 , and the other composed of the two legs $d d^1$ and the board d^2 . These two sets of legs can be swung down, as shown in Fig. 3, the frame

$a a^1 a^2$ uppermost, making a convenient wash-form. The upper ends of these legs project beyond their pivots, and when the device is adjusted, as shown in Fig. 3, these short ends sink into mortises made for them in the rear or under side of the frame-sides $a a^2$, so as to hold the wash-form stiffly in position.

By swinging the free ends of the frames $a a^1 a^2$ and $b b^1 b^2 b^3$ apart, as shown in Figs. 4 and 5, the device is adjusted into a step-ladder. It is held thus adjusted by the legs $c c^1$, having the hooks $e e$ upon their ends, taking into the loops $e' e'$, attached to the frame-sides $a a^2$.

The legs $d d^1$ can be swung out, as shown in Fig. 5, making a shelf of the board d^2 , it being supported in this adjustment by the pawl f , hinged to the cross-piece f' , hooked to b^1 , when not in use, and swinging out under the shelf d^2 , its free end resting in a corresponding mortise in the bottom of the shelf, so as to support the shelf.

I claim as my invention—

The combination of the ladder-frame $a a^1 a^2$, the supporting-frame $b b^1 b^2 b^3$, hinged thereto, and the two sets of legs $c c^1 d d^1$, pivoted to the latter, and having tenoned ends shutting into mortises in the former, all constructed, arranged, and designed for operation and use, substantially as shown and described.

CORNELIUS HOOD.
